Patented Feb. 16, 1915.

UNITED STATES PATENT OFFICE.

FRANK K. HOOVER AND ARTHUR J. MASON, OF CHICAGO, ILLINOIS.

PROCESS OF TREATING NATURAL PHOSPHATE-ROCK.

1,128,874.

Specification of Letters Patent.

Patented Feb. 16, 1915.

Application filed June 9, 1911. Serial No. 632,234.

To all whom it may concern:

Be it known that we, FRANK K. HOOVER and ARTHUR J. MASON, citizens of the United States, residing at Chicago, in the county of Cook and State of Illinois, have invented a new and Improved Process of Treating Natural Phosphate-Rock, of which the following is a specification.

This invention relates to a new and improved method of treating natural phosphate rock which is extensively used at the present time as a fertilizing agent. Phosphate rock is a natural mineral deposit occurring to a considerable extent in Tennessee and other parts of the country, being usually found at a depth of from five to thirty feet below the surface of the ground and existing in strata of varying thicknesses beneath an over-lying stratum of clay. The phosphate or brown rock deposit in its natural state is found in pieces varying from rocks of considerable size down to fine powder. The larger pieces are comparatively pure, and the present somewhat wasteful method consists in utilizing principally the larger pieces and roughly washing them to obtain the desired percentage of purity, discarding the finer material which contains a considerably greater percentage of clay and other foreign matter. As the proportion of the total material existing in the fine form is, in many localities, a very considerable percentage of the whole, it is highly desirable from the viewpoint of economy to save such fine material; but to increase its commercial value it is necessary to purify it of the contained clay; and it is the chief purpose and object of the present invention to effect such a cleaning or purification of the entire body of material, including the finer part, so as to bring the whole up to the desired or required standard of purity. We have found from extensive work on a considerable variety of the brown rock of Tennessee that the portion represented by the finer particles, that is, those smaller than one-twentieth of an inch in diameter, if properly washed, will retain nearly the same percentage of phosphate of lime as the large pieces, and our present process consists in a method of treatment whereby the whole deposit consisting of the so-called phosphate sand as well as the large lumps and rocks may be caused to yield a

resulting product which will grade substantially the same as when the large pieces only are selected. 55

Our process, as to its main or essential steps or operations, consists in, first, the rubbing and grinding of the material on itself to bring all the clay to a solvent condition; second, diluting the same thoroughly with sufficient water; and, third, the separating of the rock from the dirty water. A preliminary operation of grinding or crushing is practised when a portion of the natural material may be of such size as to require the same. These main or essential operations are, according to our invention, practised separately or independently; as 60 65 70 we have found that where it is attempted to soften and wash out the impurities in one operation, satisfactory results are not obtainable.

In order that our improved process of treatment may be more fully and clearly understood, we will explain the same in connection with the accompanying drawing wherein we have illustrated, somewhat diagrammatically, a group of devices well adapted for the carrying out of the several steps of the treatment; although it is to be understood that the performance of the several acts and operations involved in the process is by no means dependent upon the 75 80 85 particular devices herein illustrated for this purpose.

The material as received from the mine consists of a mass generally very wet and composed of pieces ranging in size from 90 that of a man's head down to extremely fine material such as impalpable powder, containing intermixed therewith a considerable amount of clay, iron and sand,—chiefly clay. For convenience we first provide a receiving 95 hopper A for this rock preferably of considerable capacity for the purpose of guarding against the intermittent operations at the mine due to weather conditions and other causes. At the lower portion of said hopper we provide a rotary feed gate B, preferably of the form and type disclosed in our Patent No. 753,076, granted Feb. 23, 1904. The rock is emitted from the receiving hopper in a continuous and regulated stream 100 and is passed through one or more pairs of crushing rolls, two being herein indicated at C and D, the rolls of the two pairs be- 105

ing spaced at different distances apart, the upper rolls being set about four inches apart and the lower rolls about a half inch apart, so as to insure the crushing of both the 5 larger and smaller pieces and effecting the reduction of the whole to the desired size for treatment. From the rolls the material falls into a device which we have denominated a mulcher shown at E. We have 10 found in treating this phosphate rock to cleanse the same of the associated clay that something more is necessary than the customary tumbling in the presence of water. We have demonstrated that if this same material is first subjected to a thorough rubbing action, such as a person subjects his 15 hands to in washing them with soap, in the presence of just sufficient water to soften and render plastic the mass, it is then 20 brought to a condition highly favorable for the next step in the process of its cleansing. A microscopic examination of phosphate rock as now marketed reveals the fact that a 25 large proportion consists of grains very much like ordinary building sand, each grain more or less coated with clay carrying some iron. If these grains be vigorously rubbed against each other in the presence of a small amount of water, a scouring effect is 30 had, so that on further rinsing with more water they will appear clean and free from this coating of clay and iron. The object of this mulcher, therefore, is to subject the mass of material to this rubbing and scouring 35 action. This device, which forms the subject matter of another application filed by us June 9, 1911, Serial No. 632,235, consists, generally stated, of a number of superimposed ring-shaped holders e and e', alternate 40 holders being mounted to rotate and the intermediate holders being either stationary or rotating in the opposite direction. As the material feeds down between these 45 holders, the portions contained in adjacent holders are rubbed against each other, and as the material is constantly and slowly passing through the holders, a very thorough and intimate rubbing of the particles of the entire mass upon and against each 50 other is obtained. We find that this rubbing and scouring action is best obtained when the material has about a consistency a little stiffer than that of mortar usually employed in plastering buildings, and for this purpose 55 we add a small tempering stream of water through a pipe F which is controlled in a manner similar to that employed in brick making in the preliminary preparation of the clay. From between the rings e and e' 60 the material falls upon a rotating plate E', from the periphery of which it is uniformly withdrawn by a stationary plow indicated at E². After the material is passed through this mulcher, its appearance and behavior 65 indicate a marked change in its condition,

and it is obvious from inspection that all the clay has been softened and loosened from the particles of phosphate rock. At this time the material resembles a pulpy mass, the majority of the particles of which 70 are phosphate rock of varying sizes.

The next step in the operation consists in bringing the clay into a condition of complete suspension in water. For this purpose the material discharged from the mulcher is 75 passed through a chute G into what we term a dasher H, which consists of a rotatable cylinder set slightly out of the horizontal and having set around its interior a series of longitudinal buckets h, and to which water is continuously supplied, as through a perforated pipe h' lying in the upper part of the cylinder. The revolution of the dasher causes the material and water intermixed therewith to be lifted by the buckets h and frequently dropped upon itself. In this way the added water thoroughly mixes with the clay, and on emission from the lower end of the dasher the material is in a suitable condition to begin the process of separation, 85 containing at this time about one and one-half parts by weight of water to one part of solid matter. This dasher constitutes the subject matter of another application filed by us June 9, 1911, Serial No. 632,236. 90

From the delivery end of the dasher the material passes through a small cone or funnel I, first into a two-part or compound separator, forming the subject matter of another application filed by us June 9, 1911, 100 Serial No. 632,237, the upper part of which separator consists of an inverted cone J having an opening at its bottom sealed by a ball valve j and provided at its top with a series of channels j' laid across the same for the purpose of diffusing the over-flow over substantially the whole area of the cone and thus producing a uniform upward current, the cone J being normally filled and brimming over. This over-flow contains, of course, mud in suspension, and with it some of the finer particles of phosphate rock. The bulk of the phosphate rock, however, piles up at the bottom of the cone, and is, from time to time, discharged by opening the valve j, and delivered, accompanied by about an equal quantity of muddy water, into an underlying tank K which constitutes the lower part of the separator. The purpose of this latter device is to thoroughly expel with clear water the mud that fails to pass off in the overflow from the cone J, and rinse the solid particles of phosphate rock. To facilitate this operation we provide within the tank K a zigzag annular passage formed between outer and inner corrugated partitions l, l', clean water being let into the lower portion of the tank K through an inlet pipe k'. This clean water entering under pressure finds its way up 105 110 115 120 125

wardly through a zigzag annular passage to the top of the tank K, and in so doing meets and intercepts with a rinsing action the descending particles of phosphate rock, the latter falling to the bottom of the tank K, and the mud rising with the upflowing stream of water. To render the upward flow in the tank K as uniform as possible and effect its diffusion over the whole area of the tank we likewise provide at the top of the latter a number of channels k^2 similar to the channels j' of the upper separator, through which the rising volume of water with the balance of the mud and some finer particles of phosphate rock in suspension therein flows, together with the overflow from cone J into a trough L, whence the entire overflow passes into a further separator operating upon the water-fall or cascade principle and consisting essentially of a tank M containing a number of vertical transverse partitions m of gradually decreasing height and forming a row of compartments having a gradually stepped relation, thereby producing a series of minute cascades delivering in succession to each other from the front to the rear end of the tank, the fine particles of the heavier phosphate rock settling to the bottoms of the several successive compartments, and the lighter particles of mud and other impurities passing off through the overflow trough m^3 . By means of this auxiliary separator, the finest particles of phosphate rock, running from 1/80 to 1/500 of an inch in diameter, and represented generally by the impalpable powder constituent, and which would be otherwise wasted in the overflow from the main separator, are recovered. Returning to the main separator, the bulk of the phosphate rock falls to the bottom of the tank K and is from time to time withdrawn through a central hole in said bottom by opening a ball valve k^3 , the material falling through a chute N into a skip-car O, whence it is conveyed through delivery troughs P into a series of draining-tanks Q. We prefer to employ two or more such draining tanks with delivery to and from each in succession in order to give time for the contained water to drain. Each tank has at its bottom a filtering-bed q composed of coarse material, such as coarse phosphate rock, crushed limestone, cinder, or any suitable material, through which the bottom of the tank is set a delivery spout q' . The water is drained off through a drain-pipe q^3 , and in order to accelerate the draining we introduce into each drain pipe a steam ejector jet or nozzle indicated at q^2 . When the drainage tank has been filled with the washed phosphate rock and given time for drainage, and is ready for the drying operation, we find that it has assumed a condition so water-packed that it will not flow

even when a very large opening as large as three feet in diameter is made in the floor of the tank or receptacle. In order to cause it to flow out of the tank, we first bore a hole through the exit opening q' from below upwardly to the full height of the material in the tank, using for this purpose an earth-boring auger of sufficient size (actually about nine inches in diameter). The material is then shoveled from the top into this hole and passes thence into an underlying feed-hopper R at the bottom which regulates the supply of material to the drying devices. While it is true that this material packs in the manner above described, yet after it has been drained and once loosened it remains in the loose condition, like ordinary building sand, and flows freely in any desired manner. The expeditious removal of the drained phosphate rock from these draining tanks has heretofore presented quite a serious problem; but operating in the manner above described the material is easily removed and the capacity of a single operator becomes very great, as high as ten tons per hour.

We find that if a tank be filled with the material described, within an hour or two, by means of a steam-ejector, it may be brought to a condition wherein the water is only about seventeen per cent. of the weight of the whole, whereas in the customary method of treating phosphate rock this material passes to the drying apparatus containing not less than twenty-five per cent. of water. When it is borne in mind that a great preponderance of the heat required to dry phosphate rock is expended in merely evaporating the contained water, it will be seen that the preliminary draining which we employ effects a substantial reduction in the fuel necessary to effect the final and artificial drying. When the material in each drain-tank is ready for drying by artificial heat, the valve q^4 at the lower end of the delivery nozzle q' is opened, and the material ejected in the manner above described flows out into the hopper R and is delivered thence by the feed-roller r through a chute S to the drier T. This latter, which forms the subject matter of another application filed by us June 9, 1911, Serial No. 632,239, consists substantially of a rotary drum t made up of a plurality of endwise connected cast-iron sections, and slung by wire ropes t' from pulleys t^2 on an overhead rotating shaft t^3 , said drum being set within an ordinary furnace chamber t^4 . The drum is suspended at a slight angle and is formed interiorly with a number of integral longitudinal concaves or scallops which pick up and tumble the material upon itself, and the drum is provided near its discharge end with an annular row of openings t^5 which serve the double function of delivering the

dry material through a discharge chute U into a skip-car V and also of permitting the back flow of the hot gases and products of combustion through the interior, as well as 5 around the exterior, of the drum; such gases and products of combustion passing off through a casing W underlying the feed devices and a flue X to the chimney. As the drum t of the drier revolves it causes the 10 material therein to be constantly alive and moving, and therefore in a favorable condition to release the steam constantly being generated. The material is thus subject to direct and intimate contact with the hot 15 gases and likewise to direct contact with the hot metal which receives its heat largely from the external exposure.

In order to clearly describe a practical mode 20 of treatment of phosphate rock beginning with the material as it comes from the mine or ore-bed and ending with the clean and dried material ready for the market, we have described all of the various steps or operations which we preferably employ, includ- 25 ing those for recovering the finest particles which have heretofore been wasted. It should be understood, however, that not all of these operations are indispensable to the obtainment of a satisfactory product in ac- 30 cordance with our present invention; the main and distinguishing acts or operations residing in the loosening of the rock from the adhering clay, the bringing of the latter thoroughly into suspension in water, and 35 the separation of the rock from the loosened and suspended clay; the other described operations being ancillary thereto and preferably carried out to secure the most satisfactory results in the character of the prod-

uct and the economy and efficiency of the process.

We claim:

1. The method of removing foreign matter from a natural mineral deposit such as phosphate rock, which consists in subject- 40 ing the phosphate ore to a mutual attrition of the components thereof in the presence of sufficient water only to form a plastic mass, thereafter subjecting the material to a tum- 45 bling action in the presence of an added 50 quantity of water to suspend all the material in water, and finally subjecting the material to uprising, classifying and rins- 55 ing currents of water.

2. The process of treating a natural min- 55 eral deposit such as phosphate rock to effect the removal of foreign matter therefrom, which consists in progressively feeding to the raw material a sufficient limited quantity of water to form a plastic mass with said ore at the completion of the next step in the process, the said next step consisting in subjecting the particles of said raw material to a mutual rubbing movement to effect an attrition of said foreign matter and the consequent formation of a plastic mass consisting of a mixture of the said water, mineral and triturated foreign matter, then adding to said mixture a sufficient quantity of water to suspend all of the material in water, and finally removing the clean ore by gravity while subject to clean- 60 ing currents of water.
